UNITED STATES PATENT OFFICE

164,639

HANDBAG OR THE LIKE

Herman Jakubovitz, Sao Paulo, Brazil

Application March 22, 1951, Serial No. 14,584

Term of patent 7 years

(Cl. D87—3)

To all whom it may concern:

Be it known that I, Herman Jakubovitz, a citizen of the United States of Brazil and a resident of Sao Paulo, State of Sao Paulo, United States of Brazil, have invented a new, original, and ornamental Design for a Handbag or the like, of which the following is a specification, reference being had to the accompanying drawings, forming part hereof and in which:

Fig. 1 is a front elevational view of a handbag or the like, showing my new design.

Fig. 2 is a side elevational view.

Fig. 3 is a rear elevational view.

I claim:

The ornamental design for a handbag or the like, substantially as shown.

HERMAN JAKUBOVITZ.
